UNITED STATES PATENT OFFICE.

CHARLES L. ZIMMERMAN, OF CHICAGO, ILLINOIS.

DESIGN FOR A LAMP-BODY.

SPECIFICATION forming part of Design No. 29,568, dated November 1, 1898.

Application filed September 24, 1898. Serial No. 691,827. Term of patent 7 years.

To all whom it may concern:

Be it known that I, CHARLES L. ZIMMERMAN, of Chicago, in the county of Cook and State of Illinois, have invented and produced 5 a new and original Design for a Portable-Lamp Body, of which the following is a specification, reference being had to the accompanying drawings, in which—

Figure 1 is a side elevation of a lamp-body 10 embodying my new design. Fig. 2 is a top plan view of the same.

As shown clearly in the drawings, the characteristic feature of the design embraces an upright cylindrical base *a*, having a somewhat convex closed upper end *a'*, joined by means of a short neck *a²* with a transverse or horizontal cylindrical liquid-reservoir *b*, arranged approximately symmetrically above the base and provided at one end with a concentrically-arranged cylindrical extension *c*, 15 forming a flame-chamber, the line of juncture between the flame-chamber and reservoir being marked by a contracted portion *c'* and

the opposite end of said chamber terminating in a flaring or bell-shaped portion *c²*, within 25 which will be seated the lens. At the upper side of the flame-chamber is a hood *d*, and at diametrically opposite points at each side of the flame-chamber are ornamental side lights *e*.

Minor features which serve to enhance the design are the beadings *f f'* of the reservoir, the milling *g* at the bottom of the base, and the ornamented inlet-cap *h* at the top of the reservoir.

I claim as my invention—
The design for a portable-lamp body, substantially as herein shown and described.

In testimony that I claim the foregoing as my invention I affix my signature hereto, in 40 the presence of two subscribing witnesses, this 22d day of September, A. D. 1898.

CHARLES L. ZIMMERMAN.
